SPARK PLUG

Alfred Candelise, Flint, Mich., assignor to General Motors Corporation, Detroit, Mich., a corporation of Delaware

Application October 6, 1958, Serial No. 765,613

6 Claims. (Cl. 313—145)

This invention relates to spark plugs and, more particularly, to an improved aircraft spark plug of the type having a cast silver centerwire section and platinum wire electrodes such as shown, for example, by United States Patents 2,162,062, issued June 13, 1939, and 2,400,917, issued May 28, 1946, to Douglas Haynes Corbin.

Spark plugs of the type covered by the aforementioned patents, i.e., having the cast silver centerwire section and platinum wire electrodes, are superior to any other presently known type of spark plug for use in extremely high output piston type aircraft engines. However, one difficulty which has been encountered with such plugs is that after prolonged periods of operation they tend to develop slight insulator cracks which originate adjacent the firing tip within the insulator centerbore and gradually work radially outwardly. Actually within the normal useful life of the present plugs of this type, as determined by the life of the electrodes, these slight cracks are generally harmless. However, such cracks do present a potential hazard in that a completely cracked insulator tip falling free of the spark plug could cause extensive damage to other components of the aircraft engine. Therefore, the occurrence of these minute cracks in the insulator tip has presented a problem standing in the way of the development of aircraft plugs having longer useful and reliable life.

The present invention has as one of its objects the provision of an aircraft spark plug of the aforementioned type having highly increased durability and reliability. Another object is the provision of an aircraft spark plug having a longer useful electrode life. More specifically, it is an object of the present invention to provide an aircraft spark plug of the type having a cast silver centerwire section and platinum electrodes, which has increased resistance to insulator failure and a longer useful life.

Other objects and advantages of the invention will appear more clearly from the following description of a preferred embodiment and from the accompanying drawings in which:

Figure 1 is a side view in partial section of a spark plug constructed in accordance with the invention;

Figure 2 is a sectional view of the bottom of a spark plug shown in Figure 1 but in larger scale; and

Figure 3 is a bottom view of the spark plug shown in Figure 1.

Referring now to Figure 1, the spark plug shown comprises a metal shell 4 having a metal shielding barrel 6 secured thereto, a ceramic insulator 8 secured concentrically within the shell-shielding barrel assembly, a centerwire assembly 10 within the centerbore of the insulator the lower and external portion of which serves as the center electrode, and a pair of platinum ground elec-

2

trodes 12 and 14 each having its outer end welded to the bottom of the shell 4 and its inner end in spaced relation to the center electrode to form a spark gap therewith. The precise structure of the metal shell-shielding barrel assembly and of the means whereby the insulator 8 is secured within this assembly forms no part of the present invention and is the same as that covered by United States patent application Serial No. 404,878, filed in the names of Wilfred A. Bychinsky and Alfred Candelise on January 19, 1954 and which is now United States Patent 2,874,323 issued February 17, 1959.

The centerbore of the insulator is formed with a lower section 16 of small diameter and an upper enlarged section 18, the junction between the two sections constituting a shoulder 20. The lower centerbore section tapers very gradually toward the firing tip of the plug, i.e., without any abrupt changes in diameter or internal flange at the tip thereof such as in the plug shown by the aforementioned United States Patent 2,400,917. Likewise, the external surface of the insulator firing tip tapers gradually toward the bottom end thereof. Thus, there are no abrupt changes in the thickness of the insulator at the lower or firing tip end thereof.

Further in accordance with the invention, the bottom portion of the centerwire comprises a spindle having a cylindrical firing tip 22, a flange 24 (see Figure 2) abutting the tip of the insulator, a cylindrical portion 26 fitting snugly within the lower end of the insulator centerbore and a shank portion 28 of reduced diameter which extends upwardly through the lower section of the centerbore and terminates with a thin curved hook the free end of which contacts the internal shoulder 20 of the insulator. If desired, the firing tip 22 instead of being cylindrical may be formed with flat side surfaces oriented parallel to the flat faces of the ground electrodes to thereby increase the spark gap area of the firing tip. The entire spindle may be of platinum or, if desired, the upper end may be of a less expensive heat-resistant metal, preferably a nickel wire secured as by welding to the platinum firing tip portion as shown at 30. Surrounding the entire shank portion of the spindle is a body of silver 32, preferably centrifugally cast in situ as described in the aforementioned United States Patent 2,400,917.

The distance between the flange 24 and the platinum ground electrodes 12 and 14 is the same as that between the respective ground electrodes and the cylindrical tip 22. Thus, one of the important functions of the flange is that it provides additional firing tip area and thereby increases the electrode life. Additionally and more important, the flange functions as a barrier against the entrance of combustion gases into the centerbore of the plug and thereby decreases the corrosive effect of these gases on the cast silver body 32. Based on the work which has been conducted in conjunction with this invention, there is reason to believe that corrosion of the silver body has a direct bearing on the problem of insulator tip cracks. If desired, additional sealing may be provided by an annular body of cement 34 between the flange and the tip of the insulator as shown in Figure 2.

A conductive glass seal 36 of a mixture of glass and nickel or copper powder abuts the upper surface of the cast silver body 32, a durable electrical connection between the silver and glass seal being formed by spiral wire 38, the lower end of which is embedded in the silver. The glass seal may be as disclosed in United States Patent 2,248,415, issued July 8, 1941 to Karl Schwartzwalder and A. S. Rulka.

The centerwire 10 of the embodiment shown has as one of its elements a resistor cartridge 40, the upper end of which is connected to a suitable contact (not shown) which serves as the means for making electrical connection of the centerwire to the ignition lead cable, as shown in the aforesaid application Serial No. 404,878.

To manufacture the plug, the platinum tipped spindle is inserted through the bottom of the insulator and the upper portion is then bent over into contact with the insulator shoulder 20, the snugly fitting cylindrical portion 26 in combination with the upper bent portion maintaining the spindle centralized within the insulator centerbore. If it is desired to provide additional sealing, a small amount of cement may be placed over the tip of the insulator or over the upper surface of the flange 24 just prior to inserting the spindle, the assembly then being heated, if required, to cure the cement. A cement which is suitable for such sealing is that covered by United States Patent 2,829,063, issued April 1, 1958 to Karl Schwartzwalder and Arthur V. Somers.

After the platinum-tipped electrode spindle is firmly secured within the insulator as described, a mass of silver is placed in the insulator centerbore from the top thereof, melted by heating and then cast, preferably centrifugally, to thereby form the dense silver body 32. Prior to hardening of the silver, the spiral wire is positioned, as shown, such that its bottom portion becomes embedded in the silver. To form the conductive glass seal, a charge of metal and glass in powder form is placed in the centerbore and the assembly heated to thereby fuse the glass, pressure being simultaneously applied so that a good bond forms between the glass mixture and the insulator. The resistor cartridge being positioned as shown, a suitable electrical contact (not shown) is then secured in place in the conventional manner. The remainder of the assembly operations may be as described in the aforesaid United States patent application Serial No. 404,878. As a final operation, the platinum ground electrodes 12 and 14 may be adjusted by bending as required to provide the desired spark gap.

By far the most important advantage of the combination of structural features shown is that it provides highly improved resistance to insulator failure. More specifically, it has been found that the centerwire-insulator assembly structure provides optimum plug life and durability with freedom from the slight insulator cracks which have heretofore developed adjacent the firing tip of cast silver centerwire type plugs after prolonged operation. This feature, in addition to the longer useful electrode life, provides a greatly improved spark plug having optimum durability and reliability.

While the invention has been described specifically with reference to a particular embodiment thereof, it is understood that changes and modifications may be made, all within the full and intended scope of the claims which follow.

What is claimed is:

1. A spark plug comprising a generally tubular metal shell having at least one platinum ground electrode wire secured to the lower end thereof, an elongated insulator having a centerbore therethrough and secured concentrically within said shell, said centerbore having a lower portion of reduced diameter and the wall thickness of said insulator diminishing gradually at the lower end thereof adjacent the ground electrode, a metal center electrode spindle having a lower firing tip portion spaced in spark gap relation to said ground electrode, a flange portion abutting the lower end of said insulator and also spaced in spark gap relation to said ground electrode, a cylindrical portion fitted snugly within the lower end of the insulator centerbore and a shank portion extending upwardly into said centerbore and embedded in a body of silver within the lower portion of said center-

bore, at least the flange and firing tip portions of said metal spindle being of platinum.

2. A spark plug comprising a generally tubular metal shell having at least one platinum ground electrode wire secured to the lower end thereof, an elongated insulator having a centerbore therethrough and secured concentrically within said shell, said centerbore having a lower portion of reduced diameter and the wall thickness of said insulator diminishing gradually at the lower end thereof adjacent the ground electrode, a metal center electrode spindle having a lower firing tip portion spaced in spark gap relation to said ground electrode, a flange portion having its upper surface in sealed relationship to the lower end of said insulator and its lower surface spaced in spark gap relation to said ground electrode, a cylindrical portion fitted snugly within the lower end of the insulator centerbore and a shank portion extending upwardly into said centerbore and embedded in a body of silver within the lower portion of said centerbore, at least the flange and firing tip portions of said metal spindle being of platinum.

3. A spark plug as set forth in claim 2 and including an annular body of sealing cement between said spindle and the lower end of the insulator.

4. A spark plug comprising a generally tubular metal shell having at least one platinum ground electrode wire secured to the lower end thereof, an elongated insulator having a centerbore therethrough and secured concentrically within said shell, said centerbore having a lower portion of reduced diameter and the wall thickness of said insulator diminishing gradually at the lower end thereof adjacent the ground electrode, a metal center electrode spindle having a lower firing tip portion spaced in spark gap relation to said ground electrode, a flange portion in sealed relationship with the lower end of said insulator and also spaced in spark gap relation to said ground electrode, a cylindrical portion fitted snugly within the lower end of the insulator centerbore and a shank portion extending upwardly into said centerbore terminating with an upper end portion in contact with said insulator, said shank portion being embedded in a body of silver within the lower portion of said centerbore, at least the flange and firing tip portions of said metal spindle being of platinum.

5. A spark plug comprising a generally tubular metal shell having at least one platinum ground electrode wire secured to the lower end thereof, an elongated insulator having a centerbore therethrough and secured concentrically within said shell, said centerbore having a lower portion of reduced diameter and the wall thickness of said insulator diminishing gradually at the lower end thereof adjacent the ground electrode, a metal center electrode spindle having a lower firing tip portion spaced in spark gap relation to said ground electrode, a flange portion abutting the lower end of said insulator and also spaced in spark gap relation to said ground electrode, a cylindrical portion fitted snugly within the lower end of the insulator centerbore and a shank portion extending upwardly into said centerbore and embedded in a body of silver within the lower portion of said centerbore, said cylindrical flange and firing tip portions of the metal spindle being of platinum and said shank portion being a nickel wire bonded to said cylindrical portion.

6. A spark plug comprising a generally tubular metal shell having at least one platinum ground electrode wire secured to the lower end thereof, an elongated insulator having a centerbore therethrough and secured concentrically within said shell, said centerbore having a lower portion of reduced diameter, an upper portion of enlarged diameter and a shoulder between said upper and lower portions, the wall thickness of said insulator diminishing gradually at the lower end thereof adjacent the ground electrode, a metal center electrode spindle having a platinum firing tip portion spaced in spark gap relation to said ground electrode, a platinum flange por-

tion abutting the lower end of said insulator and also spaced in spark gap relation to said ground electrode, a cylindrical portion fitted snugly within the lower end of the insulator centerbore and a shank portion extending upwardly through the lower portion of said centerbore 5 with a curved upper end in contact with said shoulder, said shank portion being embedded in a cast body of silver within said centerbore, and a conductive glass seal in the upper enlarged portion of said centerbore bonded in electrical contact with said body of silver.
